UNITED STATES PATENT OFFICE.

JOSEPH LUNER, OF CHICAGO, ILLINOIS.

METHOD OF ORNAMENTING WEARING-APPAREL.

971,388.

Specification of Letters Patent. Patented Sept. 27, 1910.

Application filed April 8, 1910. Serial No. 554,281.

To all whom it may concern:

Be it known that I, JOSEPH LUNER, a subject of the Empire of Austria-Hungary, and resident of Chicago, in Cook county, State 5 of Illinois, have invented certain new and useful Improvements in Methods of Ornamenting Wearing-Apparel; and I do hereby declare that the following description of my said invention, taken in connection with 10 the accompanying sheet of drawings, forms a full, clear, and exact specification.

This invention has general reference to improvements in the art of ornamenting shirt bosoms, shirt-waists and other articles 15 of wearing apparel that are starched and laundered before being worn; and it consists in the novel and peculiar method of producing ornamental designs on said wearing apparel when being laundered, as herein 20 after first fully set forth and described, and then pointed out in the claim.

In the drawings already referred to, Figure 1 is a plan view of an article of wear, ornamented in accordance with my method 25 of laundrying. Fig. 2 is a view of a portion of said article, drawn on an enlarged scale. Fig. 3 is a sectional view of the same on line $\alpha\alpha$ of Fig. 2.

Fig. 1 represents a laundered shirt, shirt- 30 waist or the like, the bosom A of which has a series of plaits B, on which the ornamental design is produced. These plaits are, preferably, quite narrow, and close together, they being approximately one-eighth of an inch 35 wide and of a sufficient number to produce a pleasing effect. In order to produce this ornamentation, the shirt or other article of wear, is first starched and laundered in the usual manner, and then the plaits are raised 40 to a vertical position, as shown at a in Figs. 2 and 3. This is best accomplished while the article of wearing apparel is still moist and warm from having been ironed flat with a flat-iron, by passing a blunt instrument, 45 such as a dull knife or dull paper cutter underneath the flat plaits and lifting them to the vertical position mentioned. This instrument must not, of necessity, be of metal, but it must be perfectly clean, and it needs 50 not be heated as long as the plaits are still warm and in a flexible condition, after which these vertical plaits are indented or crimped,

as illustrated at b , which may be done by pressing the blunt edge or back of a knife against the vertical plaits at the various 55 places where the indentations b are to appear, or these indentations may be produced by means of a pair of crimping tongs such as women are in the habit of using for hair-crimping purposes, applied to the vertically 60 standing plaits, and, if desired, the portions of these plaits between the crimps may be slightly inclined, as indicated at c , which may be effected by touching with one of the flat sides of the knife or other tool, the edges 65 of the vertical plaits between the indentations b , and thereby slightly deflecting the vertically standing portion of said plaits from their vertical position, which will heighten the ornamental effect of the design. 70

I desire to call attention to the fact that my present method of ornamenting a shirt bosom by starching and ironing is applicable only to such shirt bosoms in which the plaits and folds and the portions between and adjacent to the plaits are flat, in contradistinction to a shirt bosom having ruffled plaits, or one in which the plaits as well as the folds between the plaits are crimped or ruffled in the process of sewing. A shirt of 80 the latter class can never be ironed flat, owing to the gathered material in the plaits and the material adjacent to the plaits, while my method of ornamenting heretofore described is applicable only to flat shirt fronts. 85

A shirt ornamented as described, presents a highly artistic effect. The indentations, though preferably but slight can be easily seen, especially when viewed in artificial light, and they may be of any design adapted 90 to the purpose and can be rapidly produced after this art of ornamenting has been acquired.

Having thus fully described this invention, I claim as new and desire to secure to 95 me by Letters Patent of the United States—

The method of ornamenting starched and laundered articles of wearing apparel having a series of flat unruffled plaits and flat un-ruffled portions between and adjacent to 100 said plaits as described, consisting in starching and flat-ironing the article to be ornamented, then raising said plaits to an approximately vertical position, then indent-

ing or crimping these vertical plaits to a predetermined ornamental design to be produced, the portions between and adjacent to said vertical plaits remaining flat, as described.

In testimony that I claim the foregoing as my invention, I have hereunto set my

hand in the presence of two subscribing witnesses.

JOSEPH LUNER.
